Application December 9, 1948, Serial No. 64,305
In Great Britain December 10, 1947

8 Claims. (Cl. 200—122)

1

This invention relates to electric switches. An object of the invention is to provide a snap-action time-delay switch which is useful for controlling the high tension supply to thermionic tubes as well as for other purposes. Another object is to provide a thermal time-delay switch which is compensated for by changes in ambient temperature. Another object is to achieve the foregoing objects with a switch mechanism which is simple and economical to construct and manufacture and is reliable and durable in service.

In order that the invention may be more clearly understood, reference is made to the accompanying drawing in which

Figs. 1 and 2 are diagrams illustrating the principle of operation of the switch.

Fig. 3 is a schematic side view of one embodiment of a thermal time-delay switch according to the invention.

Referring to Fig. 1, if a spring strip 10 of bowed cross-section is held fast at one end by fixture to a suitable anchorage 11, and if a bearing or stop represented by arrow 12 is positioned to engage the convex side of the strip 10 at a point spaced from the anchorage 11, then the application to the concave side of the strip of a force represented by arrow 13 and applied at some point along the portion 14 of the strip 10 between the point of application of the bearing 12 and the free end of the strip, will have the effect of bending the portion 14 of the strip longitudinally about the bearing 12 in opposition to the spring resistance which the bowed cross-section of the strip offers to such longitudinal bending, until ultimately a condition in the bent portion 14 of the strip is reached where the resistance of the bowed cross-section is unable further to withstand the bending force, with the result that the bowed cross-section of the strip abruptly collapses to a flattened form in the region of the bearing 12 and by virtue of that collapse the portion 14 of the strip suddenly flexes about the bearing 12 and thus executes an abrupt, rapid and relatively large movement in the direction of bending, as is graphically represented in Fig. 2. In that figure, the flexure of the portion 14 is exaggerated for the purpose of illustration. Only a small advancing movement of the point of application of the bending force up to that position is critical for causing the abrupt flexing of the portion 14 of the strip, and conversely, only a small retraction of the point of application of the bending force is needed to permit the collapsed cross-section of the strip

2

to regain its bowed form and in so doing quickly re-flex the portion 14 of the strip. The bending force 13 may be applied at any point along the portion 14, but the nearer the point of application is to the bearing 12, the smaller will be the displacement of the point of application of the force 13 needed to flex the strip.

An example of a thermal switch embodying the invention will now be described with reference to Fig. 3. In radio and other apparatus employing thermionic tubes, it is customary to provide a time-delay switch for automatically connecting the high tension supply to such tubes only after the lapse of a predetermined time interval from switching on the apparatus, which is sufficient to allow the filaments or heaters of the tubes to attain their working temperature. The thermal time-delay switch schematically depicted in Fig. 3 may be employed for this purpose, as well as for other purposes. In this embodiment of the invention, the switch comprises an insulating base plate 60 on which is mounted an insulating block or pillar 61 to which one end of a spring strip 62 of bowed cross-section is rigidly fixed with its convex side facing the base plate 60, the free end of the strip carrying a contact 63. Overlying the strip is a bi-metallic strip element 64 in the form of a bridge having one end portion 65 clamped on to the fixed end of the strip 62 by means of a fixing bolt 66 which passes through the portion 65 of the bi-metallic strip, through the strip 62 and the block 61 and secures that assembly to the base plate 60. The bi-metallic strip 64 has an intermediate portion 67 spaced from the concave side of the strip 62 and a free end portion 68 which bears with its tip against the free end of the strip 62. Another strip 69, also of bridge form, has one end portion 70 secured to the block 61 by means of the bolt 66 against the convex side of the strip 62, an intermediate portion 71 spaced from the strip 62 and a free end portion 72 which bears against the convex side of the strip 62 at a point intermediate the block 61 and end 68 of strip 64. A stationary contact 73 spaced from contact 63 is carried on the free end of a further strip 74 which is fixed at its other end to the base plate 60. The bi-metallic strip 64 is provided with a heater winding 75, e. g., of nickel chrome, the turns of which are electrically insulated from strip 64, e. g., by a glass sleeving, and one end of the heater 75 is connected to a terminal 76 on the base plate 60, the other end of the heater being connected to the end 68 of the bi-metallic strip 64. The heater

circuit is completed through the strips 64, 62 and bolt 66 to a terminal 77 on the base plate 60. The fixed end of the strip 74 is connected to another terminal 78 on the base plate 60.

In the use of the switch, the circuit to be controlled by the switch is connected to the terminals 77 and 78, thereby connecting the contacts 63 and 73 in such circuit. The terminals 76 and 77 are connected to a circuit for supplying heating current to the winding 75. When the heater circuit is closed and the bi-metallic strip 64 is consequently heated, it bends towards the strip 62 under thermal expansion and thereby causes its end 68 to build up a pressure on the end of the strip 62 until the latter is caused to flex suddenly, in the manner described with reference to Figs. 1 and 2, and so close the contact 63 onto the contact 73. The time delay between the closing of the heater circuit and the closing of the switch may be adjusted by adjustment of the initial pressure of the bearing 72 on, or its spacing from, the strip 62, and the spacing of the stationary contact 73 from the contact 63. For this purpose, adjusting screws 79 and 80 are threaded through the base plate 60 and bear against the strips 69 and 74 respectively, these strips being made resilient so that they maintain engagement with their screws.

It will be appreciated that a change in ambient temperature would alter the time-delay setting of the switch, since such change would cause the bi-metallic strip 64 to bend towards or away from the strip 62 (with no current flowing in the heater winding 75) according as the ambient temperature rises or falls respectively, and to an extent depending upon the magnitude of the ambient temperature change, so that when the bi-metallic strip is heated by means of the heater winding, a shorter or longer time would be required for it to close the switch. If a rise in ambient temperature occurred sufficient to cause the bi-metallic strip 64 to snap over the strip 62, the switch contacts would close without operation of the heater 75. Accordingly, provision is made to compensate for changes in ambient temperature so as to render the time-delay setting of the switch independent of such changes. For this purpose, both the strips 69 and 74 are constituted by bi-metallic strips of the same thermal characteristics as the main bi-metallic strip 64 so that any change in ambient temperature affects the three strips equally and causes them to move in the same direction by the same amount. Thus, upon an ambient temperature rise with the heater 75 inoperative, the strip 69 bends and moves the bearing 72 away from the contact-carrying strip 62 by the same amount as the bi-metallic strip 64 bends and moves its end 68 towards the strip 62, so that such movement of the end 68 cannot abruptly flex the strip 62, and consequently the time required to heat the main bi-metallic strip 64 by means of the heater winding 75 sufficiently to cause it to effect the abrupt flexing of the strip will remain constant. Movement of strip 64 towards, and of strip 69 away from, the strip 62 as a result of ambient temperature rise would cause the gap between the contacts 63 and 73 to become less, and if the ambient temperature rise were sufficient, the contacts would close without the strip 62 having snapped over and, what is more important, without current flowing in the heater 75. This is prevented by the strip 74 being made a bi-metallic strip as above mentioned so that it bends and moves the con-

tact 73 away from contact 63 at the same rate as the latter is moved towards contact 73, and thus the gap between the contacts will be kept constant.

While a specific embodiment of the invention has been described in the foregoing, this is merely illustrative and the invention is not limited thereto since various other forms of the invention may be constructed to suit the requirements of any particular use. For example, whereas the switch of Fig. 3 is normally open and is closed upon actuation, it will be evident that change-over switches which, upon actuation, make one circuit and break another, may be constructed embodying the mechanism according to this invention. Also, the invention is applicable also to relays.

I claim:

1. A thermal switch device comprising a base member, a bowed-section spring strip, means for rigidly supporting one point of said strip relative to said base member, two bearing members in contact with said strip at points spaced from each other and from said one point longitudinally of said strip, said bearing members being so arranged as to be capable in conjunction with said means to produce a moment tending to bend said strip transversely and oppositely to its bowed section, two thermo-expansion means each interposed between one of said bearing members and said base member for causing said bearing members to increase and decrease the bending force on said strip upon a rise in temperature, said thermo-expansion means being so dimensioned in relation to each other that the increase in said moment produced by one thermo-expansion means under any variation of temperature is substantially compensated for by the decrease in said moment produced by the other thermo-expansion means under the same variation of temperature, and means for producing a difference in temperature between the two thermo-expansion means whereby to cause the strip to suddenly change its curvature.

2. An electrical switch device comprising a base member, a bowed-section spring strip, means for rigidly supporting one point of said strip relative to said base member, two bearing members in contact with said strip at points spaced from each other and from said one point longitudinally of said strip, said bearing members being so arranged as to be capable in conjunction with said means to produce a moment tending to bend said strip transversely and oppositely to its bowed section, two thermo-expansion means each interposed between one of said bearing members and said base member for causing said bearing members to increase and decrease the bending force on said strip upon a rise in temperature, said thermo-expansion means being so dimensioned in relation to each other that the increase in said moment produced by one thermo-expansion means under any variation of temperature is substantially compensated for by the decrease in said moment produced by the other thermo-expansion means under the same variation of temperature, means for producing a difference in temperature between the two thermo-expansion means whereby to cause the strip to suddenly change its curvature, a movable switch contact carried by said strip for operation by the sudden flexing thereof, a second switch contact for co-operation with said movable switch contact, and auxiliary thermo-expansive means for moving the second contact in accordance with temperature variations to

compensate for alternation of the contact gap between the movable and second switch contacts due to simultaneous and equal alterations in the temperatures of the two thermo-expansion means.

3. A thermal switch device comprising a base member, a bowed-cross-section spring strip fixed to said base member at one point, a first bearing constructed to act on said strip at a bearing point spaced from said one point to urge the strip outwardly of its curvature and substantially normally to the central tangential plane thereof, a second bearing constructed to act upon the convex side of the strip at a second bearing point intermediate said one point and said first bearing point in a direction substantially opposite to the action of said first bearing, first thermo-expansion means for moving said first bearing in its direction of action in response to variations of temperature, second thermo-expansion means for moving said second bearing in the same direction in response to similar variations in temperature, said two thermo-expansion means being so dimensioned that the relative alignment of said three points is substantially unaffected by any common variation of the temperatures of said two thermo-expansion means, and means for producing a temperature difference between said two thermo-expansion means and thereby causing the strip to flex suddenly adjacent said second bearing.

4. A thermal switch device comprising a base member, a bowed-cross-section spring strip fixed to said base member at one point, a first bearing constructed to act on said strip at a bearing point spaced from said one point to urge the strip outwardly of its curvature and substantially normally to the central tangential plane thereof, a second bearing constructed to act upon the convex side of the strip at a second bearing point intermediate said one point and said first bearing point in a direction substantially opposite to the action of said first bearing, first thermo-expansion means for moving said first bearing in its direction of action in response to variations of temperature, second thermo-expansion means for moving said second bearing in the same direction in response to similar variations in temperature, said two thermo-expansion means being so dimensioned that the relative alignment of said three points is substantially unaffected by any common variation of the temperatures of said two thermo-expansion means, and electric heating means associated with one of said thermo-expansion means for producing a temperature difference between said two thermo-expansion means and thereby causing the strip to flex suddenly adjacent said second bearing.

5. A thermal switch device comprising a base member, a bowed-cross-section spring strip fixed to said base member at one point, a first bearing constructed to act on said strip at a bearing point spaced from said one point to urge the strip outwardly of its curvature and substantially normally to the central tangential plane thereof, a second bearing constructed to act upon the convex side of the strip at a second bearing point intermediate said one point and said first bearing point in a direction substantially opposite to the action of said first bearing, a bimetallic element for moving said first bearing in its direction of action in response to variations of temperature, a second bimetallic element for moving said second bearing in the same direction in response to similar variations in temperature, said two bimetallic ele-

ments being so dimensioned that the relative alignment of said three points is substantially unaffected by any common variation of the temperatures of said two bimetallic elements and an electric heating resistance associated with one of said bimetallic elements for producing a temperature difference between said two bimetallic elements and thereby causing the strip to suddenly change its curvature adjacent said second bearing at predetermined values of the temperature difference between said two bimetallic elements.

6. A time switch device comprising a base member, a bowed-cross-section spring strip fixed to said base member at one point, a first bearing constructed to act on said strip at a bearing point spaced from said one point to urge the strip outwardly of its curvature and substantially normally to the central tangential plane thereof, a second bearing constructed to act upon the convex side of the strip at a second bearing point intermediate said one point and said first bearing point in a direction substantially opposite to the action of said first bearing, a first bimetallic strip for resiliently moving said first bearing in its direction of action in response to variations of temperature, a second bimetallic strip for moving said second bearing in the same direction in response to similar variations in temperature, said two bimetallic strips being so dimensioned that the relative alignment of said three points is substantially unaffected by any common variation of the temperatures of said two bimetallic strips and electric heating means associated with said first bimetallic strip for individually heating said first bimetallic strip and thereby causing the bowed-section strip to flex suddenly adjacent said second bearing after a predetermined time, when a predetermined voltage is applied to said heating resistance, said predetermined time being substantially independent of variations in ambient temperature.

7. An electrical switch device comprising a base member, a bowed-cross-section spring strip fixed to said base member at one point, a first bearing constructed to act on said strip at a bearing point spaced from said one point to urge the strip outwardly of its curvature and substantially normally to the central tangential plane thereof, a second bearing constructed to act upon the convex side of the strip at a second bearing point intermediate said one point and said first bearing point in a direction substantially opposite to the action of said first bearing, a first bimetallic strip for resiliently moving said first bearing in its direction of action in response to variations of temperature, a second bimetallic strip for moving said second bearing in the same direction in response to similar variations in temperature, said two bimetallic strips being so dimensioned that the relative alignment of said three points is substantially unaffected by any common variation of the temperatures of said two bimetallic strips, electric heating means associated with said first bimetallic strip for individually heating said first bimetallic strip and thereby causing the bowed-section strip to flex suddenly adjacent said second bearing after a predetermined time, when a predetermined voltage is applied to said heating resistance, said predetermined time being substantially independent of variations in ambient temperature, a movable switch contact carried by said bowed-section strip at a point further spaced from said first bearing than said one point, a bimetallic strip connected to the base of the switch device and a second switch contact for co-opera-

tion with said movable switch contact, said second contact being carried by said last-mentioned bimetallic strip for movement in substantially the same direction as said bearings under similar variations of temperature, whereby said second contact is caused to substantially follow the movement of said movable contact produced by variations of ambient temperature.

8. An electrical switch device comprising a base member, a bowed-cross-section spring strip fixed to said base member at one point, a first bearing constructed to act on said strip at a bearing point spaced from said one point to urge the strip outwardly of its curvature and substantially normally to the central tangential plane thereof, a second bearing constructed to act upon the convex side of the strip at a second bearing point intermediate said one point and said first bearing point in a direction substantially opposite to the action of said first bearing, first thermo-expansion means for moving said first bearing in its direction of action in response to variations of temperature, a second thermo-expansion means for moving said second bearing in the same direction in response to variations in temperature, 25 said two thermo-expansion means being so dimensioned that the relative alignment of said three points is substantially unaffected by any common variation of the temperatures of said

two thermo-expansion means, means for producing a temperature difference between said two thermo-expansion means and thereby causing the strip to suddenly change its curvature adjacent said second bearing, a movable switch contact operatively connected to said strip for operation by the sudden change of curvature of the strip, a second switch contact for co-operation with said movable contact, and thermo-expansive means interposed between said base and said second contact and so dimensioned as to cause said second contact to substantially follow the movements of said movable contact due to the simultaneous movement of said first and second bearings under variations of ambient temperature.
